US00D647843S

(12) **United States Design Patent**
Albritton et al.

(10) **Patent No.:** US D647,843 S
(45) **Date of Patent:** ** Nov. 1, 2011

(54) **ENERGY TRANSFER MODULE**

(75) Inventors: **Charles Wade Albritton**, Hercules, CA (US); **Brian D. West**, Oakland, CA (US)

(73) Assignee: **PVT Solar Inc.**, Fremont, CA (US)

(**) Term: **14 Years**

(21) Appl. No.: **29/343,919**

(22) Filed: **Sep. 21, 2009**

(51) **LOC (9) Cl.** 13-02

(52) **U.S. Cl.** D13/110

(58) **Field of Classification Search** D13/110, D13/101, 102, 118, 184, 199; 126/569-580, 126/584, 585, 704; 136/200, 206, 207, 246, 136/248, 253, 256, 259; 257/433, 434, 436, 257/437

See application file for complete search history.

(57) **CLAIM**

The ornamental design for energy transfer module, as shown and described.

DESCRIPTION

FIG. 1 is a perspective view of an energy transfer module showing our new design;

FIG. 2 is a left side view thereof;

FIG. 3 is a right side view thereof;

FIG. 4 is a top plan view thereof;

FIG. 5 is a front side view thereof; and,

FIG. 6 is a back side view thereof.

The text, graphics, and portion of a graphical user interface shown in broken lines form no part of the claimed design.
